William D. Bush.

UNITED STATES PATENT OFFICE.

WILLIAM D. BUSH, OF FALL RIVER, MASSACHUSETTS.

IMPROVED ROWLOCK.

Specification forming part of Letters Patent No. 33,823, dated December 3, 1861.

To all whom it may concern:

Be it known that I, WILLIAM D. BUSH, of Fall River, in the county of Bristol and State of Massachusetts, have invented a new and valuable Improvement in a Rowlock; and I do hereby declare that the following is a full and exact description of the construction and operation of the same, reference being had to the annexed drawings, making a part of this specification, in which—

Figure 1 is a perspective view of my invention. Fig. 2 is a perspective view of the socket. Fig. 3 is a perspective view of the rowlock removed from the socket. Fig. 4 is a vertical section of the socket.

My invention consists in a mode for securing a rowlock in a socket and securing a mat in a rowlock.

To enable others skilled in the art to make and use my invention, I will proceed to describe its construction and operation.

In Fig. 1, A' is the rowlock; B', the socket; D', a leather mat; E', the end of the shaft of the rowlock; a', a pin projecting one-eighth inch out of E'; b', a screw which secures the mat in a recess which is cast in the rowlock, and which is represented by F³ in Fig. 3. c c c c are holes through the cap for the purpose of securing the socket in the gunwale.

In Fig. 2, B² is the socket cast with the cap C². Its bore is rifled with a spiral groove commencing at d and ending at d².

In Fig. 3, A³ is the rowlock removed from the socket. E³ is the shaft, which is made to fit the bore of the socket. F³ is a recess cast in the rowlock, in which is secured the mat shown by D', (see Fig. 1.) a³ is a pin permanently secured in E³, (see a', Fig. 1,) one-eighth inch diameter, and which projects one-eighth inch.

In Fig. 4, C⁴ is the cap. G⁴ is the bore of the socket. d⁴ is a spiral groove cast in the bore one-eighth inch broad and one-eighth inch deep, which commences at e and ends at e⁴, making one revolution.

Operation: The rowlock and socket being constructed as herein specified, the socket being affixed in the gunwale of a boat in the usual manner, the novelty and operation may be noted. By applying the rowlock A³ (see Fig. 3) to the socket B² so that pin a³ will enter the spirally-rifled groove, (see d⁴ in Fig. 4,) its descent will make one revolution, pin a³ following the groove and appearing when the rowlock is in its proper position, as at a' in Fig. 1. By revolving the rowlock half a revolution either way when it is in its proper position in the socket, pin a' will be on the opposite side of the socket from where the spiral groove commences and ends, and the rowlock is held in the socket by pin a' and cannot be removed from it till revolved back and pin a' enters the groove at the lower end of the socket, when it may be removed by revolving it contrary from the manner of inserting it. When the oar is in the rowlock, it will be prevented from revolving far enough for pin a' to reach the groove.

In this invention I do not claim or desire to claim any devices previously invented or patented for rowlocks; but

What I do claim as my invention, and desire to secure by Letters Patent, is—

Recess F³, pin a³, and the spirally-rifled socket G⁴, constructed and operating as and for the purpose set forth.

WILLIAM D. BUSH.
